CLAIM

The ornamental design for a wireless charger, as shown and described.

DESCRIPTION

FIG. 1 is a front, left, top perspective view of the wireless charger in first state, showing my new design;

FIG. 2 is a rear, right, bottom perspective view thereof;

FIG. 3 is a rear, left perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a front, left, top perspective view of the wireless charger in second state; and,

FIG. 11 is a front, left, top perspective view of the wireless charger in third state.

The dashed broken lines in the figures are for the purposes of illustrating portions of the wireless charger that form no part of the claimed design.

1 Claim, 11 Drawing Sheets
